UNITED STATES PATENT OFFICE.

EDWIN M. ROSENBLUTH, OF PHILADELPHIA, PENNSYLVANIA.

ACETYLENE-GAS GENERATOR.

No. 815,745.

Specification of Letters Patent.

Patented March 20, 1906.

Application filed November 11, 1901. Serial No. 81,814.

To all whom it may concern:

Be it known that I, EDWIN M. ROSENBLUTH, of Philadelphia, in the State of Pennsylvania, have invented certain new and useful Improvements in Acetylene-Gas Generators, whereof the following is a specification, reference being had to the accompanying drawings.

My present improvements may be advantageously employed in vehicle-lamps, being particularly applicable to generators which are subjected to vibration during their operation and of the class wherein the supply of water gravitates to the supply of carbid.

It is the object of my invention to provide a generator wherein a charge of carbid may be retained, so that gas may be generated therefrom intermittently, the resumption of gas generation being instantaneous regardless of the extent of intermission of operation and even when the charge of carbid is partially decomposed.

My invention comprises a water-conduit and a controlling-valve for the same arranged to distribute a predetermined quantity of water over a large area of the carbid-chamber adjacent to the wall thereof, whereby instant contact of the water with the carbid is attained, and the external atmosphere is utilized in maintaining the water at a low temperature until it is in actual contact with the carbid.

My invention also comprehends means whereby the carbid is at all times excluded from the water-conduit and valve regardless of the vibration of the generator and the various novel features of construction and arrangement hereinafter more definitely specified and claimed, whereby the manufacture and operation of the generator is facilitated.

In the accompanying drawings, Figure I is a vertical sectional view of a gas-generating lamp conveniently embodying my improvements. Fig. II is a plan view of the water-column shown in Fig. I. Fig. III is a plan view of the wick shown in Fig. I. Fig. IV is a plan view of a modified form of water-column. Fig. V is a vertical sectional view taken on the line VV in Figs. I and VII. Fig. VI is a detailed view showing means for retaining the water-valve in predetermined position. Fig. VII is a plan view of the lamp shown in Fig. I. Fig. VIII is a plan view of the carbid-chamber lid shown in Fig. I. Fig.

IX is a vertical sectional view of a modified form of a gas-generating lamp.

Referring to Fig. I, the carbid-chamber 1 is provided with the lid 2, upon which is fixed the water-chamber 3. Said carbid-chamber 1 is provided with the annular flange 4 to retain the gasket 5, which is compressed to seal the joint between the carbid-chamber and its lid 2 by the engagement of the screw-thread 6 of the carbid-chamber with the screw-thread 7 of said lid.

Within the water-chamber 3 is fixed the valve-casing 8, through which water is delivered to the inlet-tube 10, projecting centrally through the lid 2. Said tube 10 is provided with a flange 11, which retains the gasket 12 in position to seal the top of the detached water-column 13, whose lower extremity is provided with the annular flange 14, which extends adjacent to the bottom wall of the floor 15 of the chamber 1. As shown in Fig. II, said flange 14 is provided with the radial water-feeding ducts 16 and the perforations 17 intermediate thereof, the arrangement being such that said casing 8, inlet-tube 10, water-column 13, and foraminous floor 14 form a conduit through which the water supplied from the chamber 3 is distributed radially outward at the bottom of said water-column adjacent to the bottom wall or floor of the carbid-chamber 1 and is thus caused to instantaneously reach a large area of the mass of carbid 19, which rests upon said flange 14. I find that the communication and distribution of the water supplied at the bottom of the carbid-chamber is facilitated by interposing the wick 21 between the flange 14 and the bottom wall 15 of the carbid-chamber, which wick is conveniently formed of a disk of textile fabric 22, saturated with an involatile liquid, such as glycerin, applied thereto in aqueous solution and subsequently coated with a powder of inert matter, such as carbid-ash 23. The flow of water through said conduit to the carbid is accurately controlled as follows: Said valve-

casing 8 receives water from the chamber 3 through the port 25, provided with the automatic check-valve 26, which is normally opened inwardly by the water in the chamber 3, but is closed when the back pressure of gas within the generator exceeds the water-pressure in said chamber.

The rate of delivery of the water 28 from

the chamber 3 through the water-conduit may be adjustably predetermined by the set of the valve 29 with respect to its seat 30 in the valve-casing 8. Said casing is provided 5 with the stuffing-box 31, secured thereto by the screw-thread 32 and comprising the screw-thread 33, engaged with the screw-thread 34 upon the valve-stem 35. The smoothly cylindrical outer extremity of said 10 valve-stem extends through the cap 36, which is in screw-threaded engagement with the stuffing-box 31, as indicated at 37, and incloses the packing 38 to seal said stem. The stem 35 is provided with the operating- 15 head 40, whose peripheral notches 41 are adapted to be engaged by the free extremity of the spring-detent 43, whose opposite extremity 44 is secured in fixed relation with the wall of the chamber 3 by being clamped 20 between the valve-casing 8 and said stuffing-box 31.

The arrangement above described is such that when the head 40 is in the position shown in Fig. VI the water-conduit is closed; 25 but rotation of said head in the direction of the arrow marked upon it withdraws the valve 29 from its seat 30, and said head is retained in any desired rotary position by the engagement of the detent-spring 43 with any 30 selected notch 41 in the head. Said head 40 is calibrated in the primary assembly of the parts to assume the position shown in Fig. VI when the valve 29 is closed as follows: The stem 35 being provided with the shoulder 35 46 (which may be of one piece therewith, but for convenience of manufacture is formed of a separate piece of metal riveted thereon) and the cylindrical stud 47, projecting in axial alignment with said stem, in the primary assembling of the parts said stem is 40 rotated until the valve 29 is closed. Then the separate head 40 is fitted upon the stud 47 in the position indicated in Fig. VI and soldered to said shoulder 46. The aforesaid 45 method of construction is advantageous in that it minimizes the amount of labor required in assembling the parts and insures uniformity in the production of the generators.

50 I find that the generation of gas is facilitated if the charge of carbid 19 is compressed in intimate contact with the foraminous flange 14, and therefore I provide the diaphragm 50, whose spring 51 compresses it 55 upon the carbid. Said spring abuts against the lid 2 and is gradually compressed as the carbid expands during decomposition and raises said diaphragm. The generated gas rising through the mass 19 to the top of the 60 chamber 1 and escaping therefrom through the gas-conduit 52 and burner 53 may be consumed in the flame 54.

The various parts of the generator are constructed and arranged with a view to minimizing the amount of time and labor re-

quired to assemble them as follows: The burner 53 is cemented in the ferrule 55, and the latter being tapered to fit the socket 56 is removably secured therein by friction. The neck 59 of said socket projects through the 70 top wall of the water-chamber 3, surrounded by the neck 57, extended from said wall. The upper extremity of the gas-conduit 52 being fitted to the socket-neck 59, both said socket 56 and conduit 52 are secured to the 75 wall of the chamber 3 by solder 58 at a single operation. Then the water-inlet provided with the screw-plug 60 is secured in the upper section of the chamber 3 by the solder 61.

As shown in Fig. VIII, the top wall or lid 80 2 of the carbid-chamber 3 comprises the central aperture 62 and the eccentric aperture 63 to respectively receive the necks 64 and 65, extended from the bottom wall of the water-chamber, and radially-extending bosses 66, 85 struck up from the metal forming said lid and perforated at 67 to receive the rivets 68, by which said lid is secured to the lower section of the water-chamber 3, with an air-space between said lid and said chamber surrounding said necks and limited by the extent of said bosses.

The water-inlet tube 10 being fitted in the neck 64, extended from the lower wall of the chamber 3, the valve-casing 8 is entered upside down through the side wall of said chamber 3. The port 25 is soldered therein, and said casing 8 being turned to the position shown in Fig. V is secured to the inlet-tube 10 by the solder 69 and to the side wall of said 100 chamber by the solder 70. Then the lower end of the gas-conduit 52 being entered through the bottom wall of the chamber 3, surrounded by the neck 65, the upper and lower sections of said chamber 3 are joined by 105 the solder 71. Then the inlet-tube 10 and neck 64 are secured to the lid 2 by the single solder joint 72, and the conduit 52 and neck 65 are secured to the lid 2 by the single solder joint 73.

110 It is to be noted from the foregoing description that the assembly of the various parts of the generator is facilitated by providing the various openings in the water-chamber 3 with necks which register with the other parts which are to be permanently secured thereto and that such construction in each instance permits three pieces to be secured together by a single solder joint, thus effecting considerable economy in the time 115 and labor required to manufacture the generator. Moreover, it being desired to maintain the water in the chamber 3 at as low a temperature as is possible and at the same time to rigidly connect it with the top wall or 120 lid 2 of the carbid-chamber, which is heated by the decomposition of the carbid, a space is afforded between said chamber and said lid through which air may be drafted to cool 125 the same by providing said lid with the inte- 130

gral bosses 66, which rigidly support said chamber 3 and by their extent limit the air-space between it and said lid, thus attaining the result specified at the minimum cost of manufacture.

Although I prefer to employ the wick 21 between the foraminous flange 14 and the floor 15 of the carbid-chamber 1, as above described, the water may be distributed 10 through said foraminous flange without the interposition of said wick, as shown in Fig. IX, which also illustrates the embodiment of my improvements in a table-lamp comprising the base-casing 75, in which the carbid-chamber is supported by its flange 4, surrounded 15 by water 76, which serves to cool said chamber.

I do not desire to limit myself to the precise arrangement or construction of my improvements which I have herein set forth, as it is obvious that various modifications may be made therein without departing from the essential features of my invention.

I claim—

25 1. In an acetylene-gas generator, the combination with a carbid-chamber provided with a water-inlet and a gas-outlet; of a water-chamber provided with a water-outlet in its wall surrounded by a neck, in integral relation with said wall; a gas-conduit extending through said water-chamber and surrounded by a neck extended from the wall thereof; said water-chamber necks being respectively entered in said water-inlet and gas-outlet in the carbid-chamber wall; bosses struck up from the metal forming the wall of said carbid-chamber; and means whereby said water-chamber is fixed to said carbid-chamber, upon said bosses, with an air-space
30 35 40 45 50 55 60 65 70 75 80 85 90 95 100 105 110 115 120 125 130 135 140 145 150 155 160 165 170 175 180 185 190 195 200 205 210 215 220 225 230 235 240 245 250 255 260 265 270 275 280 285 290 295 300 305 310 315 320 325 330 335 340 345 350 355 360 365 370 375 380 385 390 395 400 surrounding said necks and limited by the extent of said bosses, substantially as set forth.

2. In an acetylene-gas generator, the combination with a carbid-chamber; of a water-chamber above said carbid-chamber; a water-inlet tube extending from said water-chamber, within said carbid-chamber; a water-column in said carbid-chamber, in registry with said tube; and a water-feeder at the bottom of said column, consisting of an annular flange extending adjacent to the bottom of said carbid-chamber and comprising a series of radial ducts, substantially as set forth.

3. In an acetylene-gas generator, the combination with a carbid-chamber; of a water-chamber above said carbid-chamber; a water-inlet tube extending from said water-chamber to said carbid-chamber; a water-column in said carbid-chamber, in registry with said tube; and a foraminous flange secured to the bottom of said column, extending radially, adjacent to the floor of the carbid-chamber, and comprising a series of radial ducts, substantially as set forth.

4. In an acetylene-gas generator, the combination with a carbid-chamber; of a water-

chamber above said carbid-chamber; a water-inlet tube depending from said water-chamber to said carbid-chamber; a water-column separable from said carbid-chamber, but mounted within said chamber, in registry with said tube; a flange at the bottom of said column extending radially, adjacent to the floor of the carbid-chamber; and, a wick between said foraminous flange and the floor of the carbid-chamber, substantially as set forth: 75

5. In an acetylene-gas generator, the combination with a carbid-chamber; of a removable lid for said chamber; a separable water-column within said carbid-chamber; a water-inlet tube in said lid, arranged to seat on the top of said water-column; and a foraminous flange secured to the bottom of said water-column and extending radially, adjacent to the floor of the carbid-chamber, substantially as set forth. 75

6. In an acetylene-gas generator, the combination with a carbid-chamber; of a removable lid for said chamber; a water-chamber fixed upon said lid; a separable water-column within said carbid-chamber; an annular flange extending radially from the bottom of said column, adjacent to the floor of said carbid-chamber; and, a water-inlet tube extending from said water-chamber through said carbid-chamber lid, arranged to seat on the top of said water-column, substantially as set forth. 95

7. In an acetylene-gas generator, the combination with a carbid-chamber; of a removable lid for said chamber; a water-chamber fixed upon said lid; a detached water-column within said carbid-chamber; an annular flange extending radially from the bottom of said column, adjacent to the floor of said carbid-chamber; a water-inlet tube, extending from said water-chamber through said carbid-chamber lid, and provided with a resilient packing-ring to engage the top of said water-column, substantially as set forth. 100 105

8. In an acetylene-gas generator, the combination with a carbid-chamber and a water-chamber, formed of sheet metal; of necks extending from the wall of one of said chambers in integral relation therewith, and in registry with openings in the other of said chambers; a water-inlet tube seated in one of said necks; a gas-conduit seated in the other of said necks and extending through said water-chamber; and means to retain said two chambers in fixed relation, with an air-space between them surrounding said necks, substantially as set forth. 110 115 120

9. In an acetylene-gas generator, the combination with a carbid-chamber and a water-chamber formed of sheet metal; of necks extending from the wall of one of said chambers in integral relation therewith, and in registry with openings in the other of said chambers; a water - inlet tube seated in one of said necks; a gas-conduit seated in the other of 130 125

4

said necks and extending through said water-chamber; bosses struck up from the metal forming the wall of one of said chambers; and means to retain said two chambers in fixed relation with an air-space between them, surrounding said necks and limited by the extent of said bosses, substantially as set forth.

10. In an acetylene-gas generator, the combination with a carbid-chamber having a lid provided with integral bosses and two apertures; of a water-chamber above said carbid-chamber secured to said bosses, whereby an air-space is left between said chambers; the bottom wall of said water-chamber being provided with two apertures surrounded by integral flanges entered through apertures in the carbid-chamber, substantially as set forth.

11. In an acetylene-gas generator, the combination with a carbid-chamber having a lid provided with integral radial bosses and two apertures; of a water-chamber above said carbid-chamber secured to said bosses, whereby an air-space is left between said chambers; the bottom wall of said water-chamber being provided with two apertures surrounded by integral flanges entered

through apertures in the carbid-chamber, substantially as set forth.

12. In an acetylene-gas generator, the combination with a casing arranged to contain carbid; of a plate at one end of said casing provided with radial channels; means arranged to cover the normally open sides of said channels when in operative position; and, means to supply water in concentric relation with said channels, substantially as set forth.

13. In an acetylene-gas generator, the combination with a casing arranged to contain carbid; of a plate at one end of said casing provided with radial channels; a porous pad arranged to cover the normally open sides of said channels when in operative position; and, means to supply water in concentric relation with said channels, substantially as set forth.

In testimony whereof I have hereunto signed my name, at Philadelphia, Pennsylvania, this 7th day of November, 1901.

EDWIN M. ROSENBLUTH.
